UNITED STATES PATENT OFFICE

OSCAR ALVISTUR, OF OAKLAND, CALIFORNIA

AEROPLANE

Application filed March 13, 1931. Serial No. 522,425.

This invention relates to improvements in aeroplanes and has particular reference to means for retarding the landing speed of the aeroplane.

5 The principal object of this invention is to provide means whereby the forward speed of the aeroplane will be unaffected during flight but which may be retarded just previous to landing.

10 A further object is to produce a device of this character which may be incorporated in a standard aeroplane.

A further object is to provide means whereby the device will automatically operate as 15 soon as released.

A further object is to produce a device of this character which occupies a minimum amount of space.

A still further object is to produce a device 20 which is economical to manufacture and install.

Other objects and advantages will be apparent during the course of the following description.

25 In the accompanying drawings forming a part of this specification and in which like numerals are employed to designate like parts throughout the same,

Figure 1 is a perspective view of an aeroplane having my device attached thereto, and showing the retarded propeller in extending position,

Figure 2 is a fragmentary top plan view of an aeroplane showing my retarding propeller as the same would be housed in the upper surfaces of the wing structure of the aeroplane.

Figure 3 is a top plan view of the retarding propeller showing one portion of the propeller in folded position and showing the other portion of the propeller in extending position,

Figure 4 is a side elevation of an aeroplane showing my retarding propeller in extended position above the wing,

Figure 5 is a fragmentary detail view showing the mechanism for supporting my propeller and actuating the same,

Figure 6 is a side elevation of Fig. 5,

50 Figure 7 is a fragmentary detail view

showing the elevating and depressing mechanism, and

Figure 8 is a cross-sectional view taken on the line 8-8 of Fig. 5.

It is a well known fact that a large number 55 of aeroplane accidents occur due to the fact that the aeroplane lands at a speed which is high, and consequently, unless a very nice contact is made with the ground, the landing gear is liable to break due to the excessive 60 strain imposed thereon. It is therefore applicant's intention to provide a mechanism whereby the landing speed of the aeroplane may be greatly reduced thus enabling the 65 aviator to contact the ground in a more leisurely manner.

In the accompanying drawings wherein 70 for the purpose of illustration is shown a preferred embodiment of my invention, the numeral 5 designates an aeroplane as a whole having wings 6 and 7. A recess 8 is formed within the upper surfaces of the wings 6 and 7 so as to house a propeller consisting of a hub 9 to which are hingedly attached, as at 75 11 and 12, propeller sections 13 and 14 respectively. Slidably secured to these sections 13 and 14 respectively, are telescopic sections 16 and 17 respectively. These telescopic sections 16 and 17 also have slidably mounted thereon, telescopic sections 80 18 and 19, the result being, that I have formed a propeller, the blades of which are composed of telescopic sections with a result that when the telescopic sections are super-imposed one over the other, the length 85 of the blades is materially shortened, the same may rest within the pocket 8 as best shown in Fig. 2. In order to support the blades of this propeller from the hub 9, I provide supports 21 and 22 within which are 90 mounted springs 23 and 24 respectively, (see Fig. 5.) This permits the blades to move upwardly against the supports 21 and 22 or to move down slightly when the propeller is at rest against the springs 23 and 24. The hub 9 is freely rotatable upon a standard 26 which is attached to the aeroplane in any convenient manner. The lower portion of this standard 95 is provided with a key 27 which fits a key-way formed in the slider 28. This slider 100

under-lies the hub 9 and has a ratchet connection there-with as shown at 29, the purpose of which will be later seen. A pusher 31 is attached to a rack 32 which in 5 turn meshes with a gear 33. This gear may be driven in any convenient manner, the purpose of which is to elevate the rack 32, the pusher 31, and consequently, the slider 28. The first part of the upward movement of the 10 slider will merely serve to elevate the hub 9 to a point above the path of rotation of the driving propeller of the aeroplane. As soon as the slider comes in contact with threads 15 34 formed upon the standard 26, it will commence to rotate and thru the ratchet arrangement 29 will rotate the hub 9. Consequently, the telescopic sections of the retarding propeller will be thrown outwardly thru centrifugal force and will commence rotary action 20 which will also be a retarding action as well as a supporting one. This propeller will then support the aeroplane thru the helicopter principle, the propeller now rotating freely of the slider, the slider will be held in 25 elevated position by a catch 36. After a landing has been made the slider may be lowered thru the medium of the handle 37 formed upon the gear 33. The telescopic portion of the propeller may then be collapsed, and the propeller again moved into 30 its pocket in the top of the wings.

It will thus be seen that I have produced a device which will automatically operate immediately upon release to first elevate a 35 retarded propeller to a point above the path of rotation of the driving propeller, after which this retarded propeller will be given a rotary motion of sufficient intensity to cause the telescopic portions of the blade of 40 this propeller to be moved outwardly so as to increase the length of the propeller blades after which the propeller will continue to rotate under the action of the wind incident to flight, which action will cause the propeller 45 to effect a retarding action from the lending speed of the vehicle.

It is to be understood that the form of my invention herewith shown and described is to be taken as a preferred example of the 50 same and that various changes relative to the material, size, shape and arrangement of parts may be resorted to without departing from the spirit of the invention or the scope of the subjoined claims.

Having thus described my invention, I 55 claim:

1. In a device of the character described, the combination with an airplane having a winged surface, of a propeller positioned in 60 a pocket formed in the upper surface of said winged surface, a standard extending through said winged surface, said standard having a hub freely rotatable thereon, a propeller comprising a pair of telescoping blades hingedly secured to said hub, supports hingedly se- 65

cured to said blades and said hub, springs interposed in said support, whereby said blades may be flexed with respect to said hub, means for moving said hub on said standard whereby said propeller will be elevated to a 70 point above said winged surface, threads formed on said standard, a slider underlying said hub, means for holding said propeller against rotation during the initial upwardly movement of said hub, said threads imparting rotation to said hub during the balance of its upward movement.

2. In a device of the character described, an airplane having a winged surface and a driving propeller, a pocket provided in said 80 winged surface, of a standard extending upwardly through said pocket, a propeller mounted on said standard, a pair of extensible propeller blades hingedly secured to said hub, means for elevating said hub with respect to 85 said winged surface, and means for preventing rotation of said hub with respect to said standard during the initial upward movement of said hub whereby said blades will not be extended into the plane of rotation of 90 the driving propeller of the airplane until said blades have reached a point above the path of rotation of said driving propeller.

In testimony whereof I affix my signature.
